(57) **CLAIM**

The ornamental design for a food package for frozen or shelf-stable foods, as shown.

DESCRIPTION

FIG. 1 is a perspective view of a food package for frozen or shelf-stable foods.

FIG. 2 is a top plan view of the food package for frozen or shelf-stable foods of FIG. 1.

FIG. 3 is a bottom plan view of the food package for frozen or shelf-stable foods of FIG. 1.

FIG. 4 is a left elevation view of the food package for frozen or shelf-stable foods of FIG. 1.

FIG. 5 is a right elevation view of the food package for frozen or shelf-stable foods of FIG. 1.

FIG. 6 is a front elevation view of the food package for frozen or shelf-stable foods of FIG. 1; and,

FIG. 7 is a back elevation view of the food package for frozen or shelf-stable foods of FIG. 1.

In the drawings, the broken lines depict unclaimed subject matter only and form no part of the claim. The food package is shown with a symbolic break in its depth. The appearance of any portion of the article between the break lines forms no part of the claimed design.

The portion of design that does not contain surface shading forms no part of the claimed design.
